CLAIM

The ornamental design for a cereal dispenser, as shown and described.

DESCRIPTION

FIG. 1 is a top, front and right side perspective view of a cereal dispenser showing my new design;

FIG. 2 is a bottom, rear and left side perspective view thereof;

FIG. 3 is a front, bottom and left side perspective view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a left side elevational view thereof;

FIG. 9 is a right side elevational view thereof;

FIG. 10 is an exploded perspective view thereof, shown in reduced scale;

FIG. 11 is a partially enlarged view thereof, taken from FIG. 2; and,

FIG. 12 is a partially enlarged view thereof, taken from FIG. 4.

The dash broken lines show the portions of the cereal dispenser that form no part of the claimed design. The dot-dash broken line rectangle frames in FIGS. 2, 4, 11, and 12 are included to show partially enlarged views only and form no part of the claimed design.
